(57) **CLAIM**

The ornamental design for a buckle belt assembly, as shown and described.

DESCRIPTION

FIG. 1 is a perspective view of a buckle belt assembly showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is another perspective view of the buckle belt assembly shown in a state of use;

FIG. 11 is an enlarged view thereof, taken from encircled portion 11 in FIG. 2; and,

FIG. 12 is an enlarged view thereof, taken from encircled portion 12 in FIG. 3.

The broken lines in the drawings depict portions of the buckle belt assembly and form no part of the claimed design. The dot-dash broken lines in the drawings are included to show a partially enlarged view only and form no part of the claimed design.

1 Claim, 12 Drawing Sheets
